UNITED STATES PATENT OFFICE.

JOHN PYNE, OF HARRISBURG, PENNSYLVANIA.

CORNER GUARD.

Application filed March 17, 1922. Serial No. 544,608.

To all whom it may concern:

Be it known that I, JOHN PYNE, a citizen of the United States, residing at Harrisburg, in the county of Dauphin and State 5 of Pennsylvania, have invented a new and useful Corner Guard, of which the following is a specification.

This invention relates to corner guards, the object of the invention being to provide 10 a device of this character which will accurately fit within a corner adjacent to the mould board of a room to prevent dust and other foreign matter from collecting in the corner, to facilitate the cleaning of the 15 room.

Another object of the invention is to provide a device of this character which may be readily and easily stamped from sheet 20 metal by a single operation, and one which will be exceptionally durable in use.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without 30 departing from the spirit of the invention.

Referring to the drawing:

Figure 1 is an elevational view disclosing a guard constructed in accordance with the present invention as positioned in the 35 corners of stairs.

Figure 2 is an elevational view disclosing one edge of the guard.

Figure 3 is a front elevational view of the guard.

40 Figure 4 is a sectional view through the guard.

Referring to the drawing in detail, the device comprises a body portion formed of sheet metal, the same being triangular in 45 formation so that it will closely fit within a corner.

One corner of the body portion is curved inwardly as at 5, the tapered extremity thereof, and which is indicated at 6, being designed to pierce the woodwork or mould 50 board to secure the guard against movement.

The lower edge of the body portion extends inwardly as at 7 and engages the floor or step associated therewith, to prevent material from passing between the body portion and floor or step on which the same is positioned. Thus it will be seen that when a device of this character is positioned in the corner of a step adjacent to 60 the mould board thereof, the corner is guarded against foreign matter collecting therein, to the end that the person cleaning, may brush all foreign matter which ordinarily would collect in the corner, from the 65 step.

Having thus described the invention, what is claimed as new is:—

A guard comprising a triangular body portion, one corner of the body portion being curved inwardly and provided with a tapered extremity, one edge of the body portion being curved inwardly and upwardly and said tapered extremity adapted to pierce the article to which the device is secured. 75

In testimony that I claim the foregoing as my own, I have hereto affixed my signature in the presence of two witnesses.

JOHN PYNE.

Witnesses:

OWEN R. KENNEDY,
JOHN M. STEBLY.
